Primary Examiner—Stella Reid*Assistant Examiner*—I. Simmons*Attorney, Agent, or Firm*—Thomas R. Bremer; Peter G. Dilworth; Rocco S. Barrese[57] **CLAIM**

The ornamental design for a suture dispenser, as shown and described.

DESCRIPTION

FIG. 1 is a perspective view of a suture dispenser showing our new design;

FIG. 2 is a top plan view thereof;

FIG. 3 is a right side elevational view thereof, the left side elevational view being identical thereto;

FIG. 4 is a front end elevational view thereof;

FIG. 5 is a rear end elevational view thereof; and,

FIG. 6 is a bottom plan view thereof.

FIG.1

FIG.2
